ATOMIZER

Marcel Franck, New York, N. Y.

Application November 9, 1949, Serial No. 5,945

Term of patent 14 years

(Cl. D83—1)

To all whom it may concern:

Be it known that I, Marcel Franck, a citizen of France, residing at New York, in the county of New York and State of New York, have invented a new, original, and ornamental Design for an Atomizer, of which the following is a specification, reference being had to the accompanying drawing, forming part thereof.

In the drawing:

Fig. 1 is a front elevational view of an atomizer, showing my new design;

Fig. 2 is a rear elevational view;

Fig. 3 is a top plan view;

Fig. 4 is a side elevational view; and

Fig. 5 is a bottom plan view.

I claim:

The ornamental design for an atomizer, substantially as shown.

MARCEL FRANCK.
